UNITED STATES PATENT OFFICE

LARRY L. SMITH, OF MONTICELLO, KENTUCKY, ASSIGNOR OF ONE-FOURTH TO JAMES N. COX, OF COOKEVILLE, TENNESSEE, ONE-FOURTH TO CHARLES H. MOORE, OF GLASGOW, KENTUCKY, AND ONE-TENTH TO EDWARD C. WARNER, OF COOKEVILLE, TENNESSEE

TWO-WAY RADIO SIGNALING SYSTEM

Application filed July 26, 1928. Serial No. 295,541.

This invention relates to a two-way radio signaling system comprising a radio set incorporating interconnected or intercoupled transmitting and receiving circuits arranged for simultaneous transmission and reception of signals for two-way communication.

The primary object of this invention is to provide an improved, simplified and practical system for two-way radio communication in which complicated circuits requiring fine adjustments which are not practical for commercial equipment have been avoided.

In the two-way signaling system according to the present invention transmitting and receiving circuits have been combined to serve the dual functions in which the frequencies for transmitting and receiving differ sufficiently so as not to interfere with each other. In a practical form of the system the receiving circuits include a receiving antenna, detector and oscillating circuits together with suitable output amplifying circuits; the transmitting circuits include a superimposed modulating circuit which operates with the oscillator circuit which is common to both the transmission and reception of signals and a separate transmitting antenna, and a filter is connected between the receiving and transmitting circuits for preventing interference between these circuits during the simultaneous transmission and reception of signals.

The heterodyne principle of receiving is employed in which the intermediate frequency between the frequencies of the detector and oscillator circuits is passed through the intermediate frequency amplifier or filter circuit and detected in the usual way, and when acting as a transmitter the oscillator circuit is modulated by a voice frequency impressed upon it by a transmitting modulating circuit for transmitting at a different frequency from that of the incoming signals. In this way, the oscillator has a dual function acting both for input and output for simultaneously receiving and transmitting without interference.

Further objects and details of the invention will appear as described in connection

with the accompanying drawings and herein-after set forth and claimed.

The drawings illustrate preferred embodiments of the invention which have proven highly efficient and economical in operation, 55 in which:—

Figure 1 diagrammatically illustrates the principles of transmission and reception between two stations employing systems of two-way radio signaling in accordance with the 60 present invention;

Figure 2 and Figure 2A, when combined represent a circuit diagram of a radio set incorporating the two-way signaling system;

Figures 3 and 4 are circuit diagrams of 65 modified forms of the two-way signaling systems in accordance with this invention.

Referring to Figures 2 and 2A, the circuit diagram illustrated incorporates the circuits of a "super-heterodyne" receiver and transmitter circuits comprising a modulating circuit and an oscillator circuit common to both the receiver and transmitter circuits.

The circuits functioning for receiving include the detector and receiving antenna circuits D, oscillator circuits O, intermediate frequency amplifier circuits Ar, second detector circuits D₂, audio frequency amplifier circuits Aa and receiver circuit R. The circuits functioning for transmitting include the 75 transmitting modulating circuit M, the common oscillator circuits O which are common for both transmitting and receiving and transmitting antenna circuit TA.

The receiving antenna circuit of the detector circuit preferably includes an aerial 85 1, untuned primary inductance L1 of a coil 2 and ground connection 3. Coil 2 has a secondary inductance L2 connected with a variable condenser C1 for tuning the circuit 90 to the wave length of the incoming signal, and this circuit is connected with the detector tube VT1, comprising the grid circuit of this detector tube. The plate circuit of the detector tube includes a regeneration or "tickler" 95 inductance coil L3 which is inductively coupled with the coil 2. This plate circuit feeds through a receiver "pick up" inductance coil L9, inductively coupled with the oscillator circuits O to the primary of the first 100

transformer T1 of the intermediate frequency amplifier circuits.

The oscillator circuits O include an oscillator tube VT2, the grid circuit of which includes a grid oscillator inductance coil L5, a radio frequency choke coil L4 and a variable grid resistance VR1, and the plate circuit includes a plate oscillator inductance coil L7.

- 10 Inductance coils L5 and L7 are inductively coupled and capacitively connected by means of a small by-pass condenser C5 (about .0005 m. f.), for receiving incoming signals. These oscillator inductances are tuned by means of 15 a variable condenser C2. These inductances are inductively coupled with the inductance coil L9, referred to above as being connected in the plate circuit of the detector tube VT1 and the first transformer T1 of the intermediate 20 frequency amplifiers, whereby the frequency of the oscillator circuit is impressed upon that of the detector circuits for producing a certain heterodyne frequency hereinafter described in detail to which the intermediate frequency amplifiers will respond.

The intermediate frequency amplifying circuits comprise a number of stages each having an amplifying tube VT4 and amplifying transformers T1 and T2. The transformer T1 which feeds into the first amplifying tube has a tuned primary winding which responds to said heterodyned frequency referred to above. The primary winding 4 of this transformer is connected with a condenser C6 which may be semi-variable or adjustable for adjusting the wave length of this circuit to the desired frequency found to be most efficient for the intermediate or heterodyned frequency amplifier circuits in 30 the two-way signaling systems and also functioning as a filter or by-pass to prevent interference between the transmitting and receiving circuits as will be hereinafter described. The secondary winding of this 35 transformer is connected with the grid of the first amplifying tube and the plate of this tube and each tube of the succeeding stages feeds into the primaries of the transformers T2 and, similarly, the secondaries of the 40 transformers T2 feed into the grid of the next tube. The returns of the secondary windings of transformers T1 and T2 are connected with a potentiometer 5 across the filament or "A" battery and with the common negative of the "A" and "B" batteries, or other sources of current through a by-pass condenser C7 in the well known manner.

The secondary winding of the last transformer T2 feeds into the grid of detector tube VT5 of the second detector circuits D₂, this grid circuit including the grid leak resistance R2 and grid condenser C9. A by-pass condenser C8 may be connected across the plate circuit of this detector tube VT5, which circuit feeds into the audio frequency ampli-

fying circuits Aa in the usual manner. The audio frequency amplifier circuits, as shown, include two audio transformers AT-1 and two audio amplifying tubes VT6 which are in turn connected with the receiver R. The various circuits are supplied with current at the desired potentials in the usual manner and the various tubes may be controlled by means of rheostats or filament ballast resistance R3. A negative grid potential provided by a battery C-B2 may be employed in the circuits of the audio amplifier tubes to advantage.

The circuits above described comprise the receiving circuits of the "super-heterodyne" receiver of the two-way signaling system and in operation its tuning is controlled by means of the two variable condensers C1 and C2, condenser C1 being adjusted for tuning the detector circuits D to the wave length of the incoming signal and condenser C2 being adjusted to tune the oscillator circuits O to a frequency to produce with the frequency of the detector circuits a heterodyne frequency to which the tuned intermediate frequency amplifier circuits Ar have been adjusted to respond. The signals are then passed through the second detector circuits D₂ and audio frequency amplifier circuits Aa and receiver circuit R.

In the transmitting circuits, the transmitting modulating circuits M include a microphone MK5 and modulating transformer Mod-T connected in the grid circuit of the transmitting modulating tube VT3 to which a negative grid bias potential may be supplied by a battery O-B1.

The plate circuit of this modulating tube is connected through a radio frequency choke coil L8 with the plate coil L7 of the oscillator inductances. The B battery current for both the oscillator tube VT2 (which serves the dual function in the two-way signaling system) and the transmitting modulating tube VT3 is supplied to these tubes through an audio frequency choke coil H1-1 directly to the plate of tube VT3 and through the radio frequency choke coil L8 and plate oscillator coil L7 to the plate of tube VT2. A milliammeter mm' may be connected in this circuit to indicate the power supplied to these tubes which may be regulated according to distances and transmitting conditions. The audio frequency choke coil H1-1 is effective in maintaining a constant supply of power to the two tubes during the modulation of the power delivered through the oscillator tube when an audio frequency is impressed on the grid of the modulator tube VT3. The radio frequency choke coil L8 is effective to prevent the radio frequency currents in the oscillator circuit from passing and thereby prevents interference with the functioning of the oscillator.

The oscillator circuits have been described

in connection with the receiving circuits and the inter-connection of the transmitting modulator circuits and the oscillator circuits. 100 have been set forth above as well as the manner in which the power in the tuned oscillator circuit is modulated by means of the audio frequency modulator tube VT3. The tuning of the oscillator has also been described in connection with the receiving circuits as being

accomplished with the variable condenser C2. Although not always necessary, the plate circuit may also be tuned with a variable condenser C3. However, as herein-after set forth, tuning of the oscillator may be best accomplished by omitting the plate condenser C3 and bridging the grid coil L5 with the condenser C2.

The transmitting antenna circuit Ta includes an aerial 6 connected at one end of the 20 antenna inductance or transmitter aerial pick-up coil L6 which is positioned between the oscillator inductances L5 and L7, and a ground or counterpoise 7 connection with the other end of the coil L6. The aerial is tuned 25 for transmitting by means of a variable condenser C4 also in the antenna circuit.

The operation of the system for receiving has been described in connection with the receiving circuits of the system and for transmitting, above. It will be noted that the oscillator circuits are tuned to a required frequency which serves a dual function, being effective to produce the carrier wave in the transmitting antenna circuit Ta and cooperating 35 with the frequency of the incoming signal as tuned in by the detector circuits D to produce a heterodyned frequency to pass through the intermediate frequency circuits Ar for receiving.

With the set properly adjusted transmitting and receiving at the same period of time has been accomplished. In order that the audio-frequency variations of the oscillator output will not be transmitted to the intermediate frequency amplifier along with the 40 audio-frequency variations due to the incoming signal, the adjustable condenser C6 used to tune the first intermediate amplifier T', as hereinbefore referred to, is also used as a bypass for such oscillator variations as may be present in that part of the circuit. Further, it will be noted that the first input tube, VT1, is used as a modulator at radio frequency, rather than the usual form of detector; this 45 is due to the fact that the usual grid leak resistance and condenser are omitted and thereby the amplifying action of this tube tends to make the receiver part of the set more sensitive. This manner in which the first tube VT1, is used is probably the reason why there 50 is no interference on the receiver while transmitting or modulating the carrier frequency as it was found that when this tube was used as a detector with the customary grid leak and condenser there was quite a lot of feed

back to the first part of the instrument, causing disturbance in the second detector output. This was overcome by omitting the grid leak resistance and condenser from this first tube circuit and therefore the first or input tube VT1 is not used as a detector tube, but as a modulator at radio frequency, and no part of this circuit is sensitive to audio-frequency variation.

Referring to Figure 1, an application of 75 the two-way signaling system between two stations is illustrated. It will be noted that each station is equipped with two aerials, one for transmitting and one for receiving. Station No. 1 is tuned to receive on 100 meters wave length and to transmit on 103 meters and station No. 2 receives on 103 meters and transmits on 100 meters, that is 100 and 103 80 correspond to the respective wave lengths of the oscillating circuits of the two stations and their receiving wave lengths differ by three meters corresponding to the frequency of approximately eighty-seven kilocycles at said wave length range, namely, 100 and 103 meters to which the tuned intermediate or heterodyned frequency amplifier circuits of the 85 systems are adjusted to respond.

Referring to Figure 3, a simplified form of the system in accordance with this invention is diagrammatically shown. With but a few exceptions the detector, oscillator and modulator circuits are the same as those shown in Figures 2 and 2A, the same characters of reference being used to denote the similar parts. In the oscillator circuits, it will be noted that the variable condenser C2 has been arranged to bridge the grid coil L5 of the oscillator inductances as mentioned hereinbefore, and the plate tuning condenser C3 has been omitted. Otherwise, these 95 circuits are the same. In this case, the heterodyned frequency is fed into a tuned intermediate frequency amplifier consisting of primary and secondary coupled inductances L10 and L11 respectively which is provided 100 with a primary semi-variable or adjustable condenser C6 for tuning it. The intermediate frequency amplifier feeds into the second detector tube VT5 to which the receiver R is 105 connected.

Referring to Figure 4, the circuit arrangements are substantially the same as that represented in Figure 3 with the exception that a double grid tube VT7 is used in place of both the oscillator tube VT2 and transmitting 110 modulator tube VT3. In this arrangement the oscillator grid inductance coil L5 is connected with one grid H2 of this tube and the modulating transformer Mod-T is connected with the other grid H1 thereof. Using 115 a four element tube in accordance with this arrangement has advantages over corresponding systems employing three element tubes in that the system can be put up in a more compact set, eliminates the necessity for a 120 125

number of extra parts and connections and reduces the current consumption to some extent.

The operation of systems disclosed in Figures 3 and 4 is the same as that of the system shown in Figures 2 and 2A. These systems have been simplified but still maintain the same principles of the invention.

The novel features which are believed to be inherent in the invention are defined in the appended claims.

I claim:—

1. In a two-way radio signaling system, the combination with a receiver including 15 detector, oscillator and intermediate or heterodyned frequency amplifier circuits, of a transmitter for operating simultaneously therewith including separate modulating and antenna circuits coupled by the oscillator circuit of the receiver, and a filter between the modulating circuit and oscillator circuit operative to prevent the passage of radio frequency currents from the oscillator circuit.

2. In a two-way radio signaling system, 25 the combination of receiving antenna and detector circuits, an oscillating circuit cooperating therewith, an intermediate frequency circuit responsive to a heterodyned frequency between the frequencies of the detector and oscillator circuits for receiving incoming signals, means for simultaneously modulating the current in the oscillator circuit by an audio frequency, said oscillating circuit including a single two grid oscillator 35 tube of which one of the tube grids functions in the oscillator circuit in the production of high frequency oscillations for both receiving and transmitting and the other grid is connected with the transmitting audio frequency modulating means, and a radiating circuit coupled with said tube for transmitting oscillations of said oscillator as modulated by the audio frequency.

3. In a two-way radio signaling system, 45 the combination of a receiver and transmitter including a two grid oscillator tube, one grid of which tube functions in the production of continuous high frequency oscillations for both the receiver and transmitter to provide 50 a common oscillator, the other grid of said oscillator tube being included in the transmitting circuit and operative to modulate the high frequency oscillations in accordance with the impressed audio frequency for 55 transmitting outgoing signals.

4. In a two-way radio signaling system, including a receiver and intercoupled transmitter for receiving and transmitting on separate wave lengths simultaneously, said 60 receiver consisting of a receiving antenna circuit tuned to one frequency, an oscillator tuned to a different frequency, and amplifying and detecting circuits including an intermediate frequency amplifier tuned to respond to the heterodyned frequency between

the frequency of the receiving antenna circuit and frequency of the oscillator, and said transmitter including a modulator connected with said oscillator of the receiver, and a radiating circuit inductively coupled with 70 said oscillator for transmitting at the frequency of the oscillator.

5. In a two-way radio signaling system, the combination with a receiver including, a receiving antenna circuit, an oscillator co-operating therewith, and an intermediate tuned frequency circuit responding to the differences in frequency between the receiving antenna circuit and said oscillator, and a receiving detector connected with the last 80 said circuit, of a transmitter including a modulating circuit connected with said oscillator, and a separate transmitting antenna coupled with said oscillator.

6. In a combined radio signal receiving and transmitting apparatus, an antenna for receiving an incoming signal including a tuned circuit connected therewith, means for heterodyning said incoming signal including an oscillator which oscillates at a different 90 frequency from that of the incoming signals, an intermediate circuit, a detector and a receiver connected therewith, a transmitting radiating circuit coupled to the oscillator, means for modulating the oscillations of said oscillator for transmitting signals at the frequency of said oscillator, and a filter or a bypass connected between the transmitting and receiving circuits to prevent interference between the transmitter and receiver and for 100 tuning said intermediate circuit to the frequency difference between the frequency of the incoming signal and the frequency of the oscillator.

7. In a two-way radio signaling system, 105 the combination with a receiver including an oscillating circuit with its oscillating tube, a transmitting modulator coupled therewith including a modulating tube, a source for supplying current to the plates of both the oscillating and modulating tubes, means to prevent audio variations in the current supplied to the plates of the two tubes, and means to prevent radio frequency currents from passing between the plates of the two tubes, 110 of a filter or by-pass connected with the receiving circuits operating to by-pass variations in amplitude of the oscillator due to the modulator and prevent such variations from being detected in the receiving circuits, thereby preventing the transmitter from interfering with the receiver, whereby the interconnected transmitter and receiver may function independently and simultaneously.

In testimony whereof I hereunto affix my 125 signature.

LARRY L. SMITH.
